COMBINED ASH TRAY, CIGARETTE REST, AND EXTINGUISHER

Ewald W. Terney, Mineola, N. Y.

Application November 2, 1954, Serial No. 32,930

Term of patent 14 years

(Cl. D85—2)

Fig. 1.

Fig. 2.

Fig. 3.

Fig. 1 is a perspective view of a combined ash tray, cigarette rest, and extinguisher, showing my new design.

Fig. 2 is a side elevational view of the same.

Fig. 3 is a sectional view taken on the line 3—3 of Fig. 2.

I claim:

The ornamental design for a combined ash tray, cigarette rest, and extinguisher, as shown.
